UNITED STATES PATENT OFFICE.

GERHARD DERKSEN, OF HALES CORNERS, WISCONSIN.

LIFTING-JACK.

1,356,699.

Specification of Letters Patent. Patented Oct. 26, 1920.

Application filed January 26, 1920. Serial No. 354,188.

To all whom it may concern:

Be it known that I, GERHARD DERKSEN, a citizen of the United States, and resident of Hales Corners, in the county of Milwaukee and State of Wisconsin, have invented certain new and useful Improvements in Lifting-Jacks; and I do hereby declare that the following is a full, clear, and exact description thereof:

My invention relates to lifting jacks, its primary object being to provide a lifting jack unit which is simple, durable and arranged to be manipulated to lift a load with the least possible power, due to the arrangements of the levers.

Another object of my invention is particularly to provide a set of such lifting jacks for the purpose of raising a vehicle, having pneumatic tires, from the floor whereby load strain is relieved from said tires.

Still another object is to provide a construction wherein the parts can be manufactured at a minimum cost due to the elimination of machine work.

A still further object is to provide means for adjusting various elements of the jack to meet the conditions of different sized wheels, and a still further object is to provide a jack embodying a system of levers for accomplishing the raising and lowering function without the use of worms or screws whereby wear and expensive structure is avoided, while at the same time quickness of action can be effected.

While the jack units may be used separately as in ordinary cases, it is my intention to provide a set of four jacks for each vehicle whereby they can be applied to the vehicle when the same is in storage to raise it from the floor quickly, and due to the leverage action when raised, the jack will automatically lock in such raised position.

With the above and other minor objects in view, the invention consists in certain peculiarities of construction, combination and arrangement of parts as set forth herein-after with reference to the accompanying drawing and subsequently claimed.

In the drawing:

Figure 1 represents a sectional elevation of a jack embodying the features of my invention, the section being indicated by the line 1—1 of Fig. 2, said view showing the jack elements in their lifted position and

adjusted to the hub of a wheel, the said wheel being indicated by dotted lines.

Fig. 2 is a face view of the jack, showing certain parts in section to more clearly illustrate the structural features.

Referring by characters to the drawing, 1 represents a base yoke having slotted arms 2 which are adapted to receive the standards 3 that are preferably formed with edge flanges to provide strength, which flanges are connected by web portions, as best shown in Fig. 1. The standards are secured to the arms 2 by suitable bolts 3' and due to the slotted connections, these arms may be adjusted so as to vary the length of the jack frame. The standards have inwardly extended trunnions 4 to which are pivoted the bowed legs 5 of a hand lever 6, the same terminating with a convenient hand-grip as best shown in Fig. 2.

In order to vary the length of this hand lever, I provide the grip portion with a stem 7 which is slotted at 7' throughout its length for the reception of a clamping bolt 9, which clamping bolt passes through the slot in the stem of the handle and also through the upper terminal of the legs 5. Thus it will be seen that the stem of the handle can be lengthened and shortened so as to increase and diminish the leverage. The legs of the hand lever are also formed with apertures 10 therein which are slightly offset from a line intersecting the central portion of the lever and its fulcrum points 4, as best shown in Fig. 1. These apertures 10 are adapted to receive bearing lugs 11 of a link 12. The lower portion of the link, as best shown in Fig. 2, is curved and has fitted to its throat portion a flexible shield 13, which shield is adapted to have contact with a hub 14 of the wheel and thus protect it from abrasions.

The throat portion of the hub lifting link has extending therefrom, a pair of guide-pins 15, which pins are adapted to ride upon the inner surface X of the standards. In order to provide adjustment as to length of the jack frame at its upper end, the standards have fitted thereto extension straps 16. The straps are slotted for the reception of a tie bolt 17 that is provided with suitable jam nuts 17' and clamping nuts 18, the ends of the tie bolt being extended through suitable apertures that are

- formed in the standards. Thus it will be seen that the straps may be adjusted vertically and locked in their adjusted position by tightening the nuts 18. At the same time while this tie bolt 17 forms a means to permit adjustment of the straps, it also forms a brace for the upper portion of the jack frame. Attention is directed to the fact that, as shown in Fig. 1, the hub of the vehicle is cylindrical in form and hence there is no liability of the link slipping off when subjected to lifting strain. Should the hub be tapered outwardly and toward the axis of the wheel, I preferably provide a clamping ring which is secured to such inclined hubs to prevent slippage of the link. This structure, however, forms no part of my invention and therefore is not illustrated.
- From the foregoing description, it will be seen that in operation the upper and lower ends of the jack are adjusted to accommodate it in length to the diameter of the wheel with respect to its axis, and in order to raise the wheel from the floor, the jack frame is nested against the outer face of the tire and in this position the handle or lever 6 is swung downwardly so that the throat portion 13 of the link is quite a distance below the hub, which hub projects through the frame.
- The operator simply raises the handle or lever to the position shown in Fig. 1, and due to its rotation upon the trunnions 4, the hand lever will cause the link to ride upwardly engaging the lower surface of the hub to lift the same as indicated in Fig. 1, thus raising the tread of the wheel from the ground, and as this action takes place, it will be observed that the bearing lugs 11 which constitute the pivot points for the link, will ride past or over an imaginary line intersecting the longitudinal axis of the lifting lever 6 and its fulcrum point. Hence the load strain upon the link has been shifted to a position where said load strain will serve to hold the lever in its normal upright position as shown in Fig. 1, and any tendency of said lever to move farther inwardly or toward the wheel is overcome, due to the fact that the legs of the lever engage stop lugs 19 which project from the frame standards from the path of travel of the aforesaid lever legs.
- It will be observed that owing to the simple lever and link connection, a heavy load

can be readily manipulated with a minimum amount of power and that the jack will operate instantaneously.

While I have shown and described various minor structural features with reference to the exemplification of my invention, it is understood that I do not wish to be limited to such features. 60

I claim:

1. A lifting jack comprising standards, means for adjusting the length of the standards with relation to their upper and lower ends, trunnions extending from the standards, a lever having bowed legs in pivotal union with the trunnions, the levers being positioned between said standards, a link having lugs pivotally connected to the legs of the lever at a predetermined point from the trunnion connection, guide pins extending from the lower portion of the link adapted to engage the sides of the standards, means extending from the standards to limit movement of the lever legs in one direction, and means for adjusting the length of the 75 lever. 70

2. A lifting jack comprising standards, means for adjusting the length of the standards with relation to their upper and lower ends, trunnions extending from the standards, a lever having bowed lugs in pivotal union with the trunnions, the levers being positioned between said standards, a link having lugs pivotally connected to the legs of the lever at a predetermined point from the trunnion connection, guide pins extending from the lower portion of the link adapted to engage the sides of the standards. 85 90

3. A lifting jack comprising standards, means for adjusting the length of the standards with relation to their upper and lower ends, trunnions extending from the standards, a lever having bowed legs in pivotal union with the trunnions, the levers being positioned between said standards, a link having lugs pivotally connected to the legs of the lever at a predetermined point from the trunnion connection, guide pins extending from the lower portion of the link adapted to engage the sides of the standards, and means for adjusting the length of the 100 lever. 95

In testimony that I claim the foregoing I have hereunto set my hand at Hales Corners, in the county of Milwaukee, and State of 11 Wisconsin.

GERHARD DERKSEN.
